CLAIM

The ornamental design for pet bed, as shown and described.

DESCRIPTION

FIG. 1 is a perspective view of a pet bed showing my new design;

FIG. 2 is a top view thereof;

FIG. 3 is a front elevational view thereof;

FIG. 4 is a rear elevational view thereof;

FIG. 5 is an end elevational view thereof, the opposite end view being a mirror image of that shown in FIG. 5;

FIG. 6 is a perspective view of a second embodiment of FIG. 1;

FIG. 7 is a top view of FIG. 1;

FIG. 8 is a front elevational view of FIG. 1;

FIG. 9 is a rear elevational view of FIG. 1 ; and,

FIG. 10 is an end elevational view of FIG. 1, the opposite end view being a mirror image of that shown in FIG. 10.
